EDWARD M. BRACKETT AND FRED M. BRACKETT, OF TOPEKA, KANSAS.

ADJUSTABLE CUTTING-OFF MECHANISM FOR STRIPPING MACHINES.

Application filed August 2, 1926. Serial No. 126,450.

Our invention relates to a cutting off mechanism and more particularly to an adjustable cutting off mechanism for stripping machines.

5 It is a purpose of our invention to provide a machine for applying a strip to a pair of sheets or sheet-like members that are arranged with their sides adjacent each other, with means for severing said strip at predetermined points to leave said articles connected together in pairs by means of said strip connecting the adjoining edges thereof.

10 As the sheet like members, which may be a single sheet or a plurality of sheets arranged in superposed relation to which a sheet is secured by means of a strip, are of various dimensions, it is desirable to provide means for adjusting the cutting off mechanism so that the width of the sheets 15 may be compensated for. It is accordingly a purpose of our invention to provide cutting off mechanism in a machine of the above mentioned character which comprises a rotatable member having a cutting member 20 mounted thereon, said rotatable member being adjustable transversely of the feeding means that conveys the articles secured together by the strips toward said cutting off mechanism.

25 It is a further purpose of our invention to provide means lying in the path of the articles to be acted upon by the cutting off means, for actuating the cutting means and to provide actuating means for said cutting off 30 means that is so mounted that certain portions thereof are movable with the cutting off mechanism transversely of the feeding means while certain other portions thereof are mounted in a predetermined relation to the means lying in the path of the articles, 35 which means is mounted on the framework of the machine and is not transversely movable.

40 It is a further purpose of the invention to provide means for periodically actuating the cutting off mechanism comprising a rotatable member carrying a cutting off knife, a member that constantly rotates and means adapted to connect the constantly rotating member with the rotatable member, said means 45 engaging a stop controlled by the movement of the articles carried forwardly by the feeding means and further comprising a

resilient member interposed between the rotatable member and the means adapted to 55 connect the rotatable member with the constantly rotating member which resilient means is held under tension when the stop is engaged and which resilient means is adapted to move the means interposed between 60 the rotatable member and the constantly rotating member into engaging position to rotate the rotatable member when said stop moves out of engagement.

65 Other objects and advantages of the invention will appear as the description of the accompanying drawings proceeds. However, we desire to have it distinctly understood that we do not intend to limit ourselves to the exact details shown or described, but 70 that we intend to include as part of our invention all such obvious changes and modifications of parts as would occur to a person skilled in this art and as would fall within the scope of the claims.

75 In the drawings:

Fig. 1 is a perspective view, partly broken away, of a stripping machine, showing our improved cutting off mechanism applied thereto.

80 Fig. 2 is a fragmentary end view thereof.

Fig. 3 is a fragmentary elevational view of the cutting off mechanism as viewed from the opposite side thereof from Fig. 2.

85 Fig. 4 is a fragmentary view, partly in elevation and partly in section, on a plane taken at right angles to Fig. 3.

Fig. 5 is a perspective view of the intermittent driving mechanism for the cutting off means, showing the same separated.

90 Fig. 6 is a longitudinal, sectional view thereof taken substantially on the line 6—6 of Fig. 8.

Fig. 7 is a section taken on the line 7—7 of Fig. 6, looking in the direction of the arrows.

95 Fig. 8 is a section taken on the line 8—8 of Fig. 6, looking in the direction of the arrows.

Fig. 9 is a fragmentary perspective view of the article actuated tripping means for 100 the cutting off mechanism.

Fig. 10 is a perspective view of the rotatable clutch device co-operating with said tripping means.

105 Fig. 11 is a longitudinal sectional view thereof.

Fig. 12 is a perspective view, partly broken away, of the slidably mounted rotatable clutch releasing member.

Fig. 13 is a fragmentary perspective view 5 of a portion of the clutch stop releasing means.

Fig. 14 is a fragmentary section taken on the line 14—14 of Fig. 2.

Fig. 15 is a fragmentary perspective view 10 of the paired sheets and connecting strips.

Referring in detail to the drawings:

Our improved cutting off mechanism is shown as being applied to a stripping machine having a framework 20 on which are 15 mounted the conveyor belts 21 and 22 which operate to move the articles to which a binding strip has been applied, toward the left in Fig. 1 said articles comprising the sheet-like members 23 and 24, secured together 20 by means of the strip 25. Said strip 25 is continuous, and in order to separate the articles, which may be pamphlets or similar articles having sheets secured by a strip such as the strip 25, from each other, it is necessary to sever the strip 25 adjacent the edges 25 of the sheets 23 and 24, and our improved cutting off mechanism is provided to accomplish this purpose.

Mounted on the framework 20 is a bracket 30 member 26 (Figs. 1 and 9) which is secured to one of the members of the framework in any suitable manner as by means of the securing members 27. The bracket member 26 is in the form of a block as shown in Figs. 1 35 and 9 and is inset in the framework so that the upper surface thereof is substantially flush with the frame member upon which the same is mounted. Said bracket member 26 is provided with an opening 28 therein 40 through which the fingers or arms 29 provided on the star wheel 30 are adapted to project. The star wheel 30 is preferably mounted on a shaft 31 that extends through the outer wall of the bracket 26 so as to be journaled therein, and is adapted to be 45 rotated by engagement of the articles moved along by the conveyor of the machine with the bevelled outer ends 32 of the arms 29. In order to assure engagement of the articles 50 with the arms 29 a presser member 33 is provided which is pivoted on the framework at 34 and which has a bifurcated lower end providing the arms 35 having an opening 36 therebetween, said member 33 engaging 55 with the upper surface of the block 26 by gravity and the articles carried by the conveyor moving into engagement with the inclined portion of the member 33 will raise the member 33 sufficiently to permit said 60 articles to pass thereunder but hold the same in engagement with the upper face of the member 26 so that said members will engage with one of the arms 29 to rotate the star wheel such a distance that the next arm 29 65 will be in position to be engaged by the

next article moving along with the conveyor.

Co-operating with the star wheel 30 is a lever 37 pivotally mounted at 38 upon the framework. The lever 37 is provided with an offset arm 39 at the outer end thereof which has a bevelled end portion 40 adapted to be engaged by the arms or fingers 29 on the star wheel 30 to move the lever 37 around its pivot 38 in a clockwise direction, as viewed in Figs. 1 and 9.

A spring finger 41 which has a coiled portion 42 is secured to the arm 39 by means of any suitable securing member 44 and engages with the star wheel 30 as shown in Fig. 4 so as to hold one of the members 29 80 in position to be engaged by the member 24 to rotate the star wheel through the distance from one member 29 to the next member 29. The lever 37 is normally held in the position shown in Figs. 1 and 4, by means of a 85 spring 45 which has a hooked end 46 extending through the thickened portion 47 of the lever 37 and which has a coiled portion 48 extending around the shaft 38 and an end portion 49 extending into a suitable 90 opening 50 in the framework.

Co-operating with the lever 37 is a rotatable member 51 mounted on the shaft 52 to rotate therewith and having the tapering ears or fingers 53 extending outwardly 95 therefrom at substantially diametrically opposed points, the members 53 being provided with the flat faces 54 which are adapted to engage with a shoulder 55 provided on the lever 37 when the lever 37 is in the position shown in Figs. 1 and 4. The rotatable member 51 is not positively connected with the shaft 52 but is frictionally driven thereby through the layer of friction material 56 mounted between the disk like flange 57 pinned or secured in any other manner to the shaft 52 so as to rotate therewith, and the flat face of the member 51. The member 51 is held yieldingly in engagement with the friction material 56 by means of a coiled 100 spring 58 mounted between the disk or washer 59 and the member 51, the tension of the spring 58 being adjusted by means of the nut 60 engaging the screw threaded end 61 of the shaft 52. The disk 57 bears against a shoulder 62 provided on the shaft 52. Accordingly, when the member 51 has one of the projecting wings 53 thereof in engagement with the shoulder 55, the shaft 52 will rotate without rotating the member 51. However, should the lever 37 be moved out of its normal position by one of the members 29 engaging with the bevelled end 40 thereof, the member 53 will be disengaged from the shoulder 55 and the member 51 will rotate. This rotation, however, will only be through half a revolution of the member 51 because the other member 53 will then engage with the shoulder 55 in view 110 of the fact that the lever 37 will have been 115 120 125 130

restored to normal position by means of the spring 45.

Secured to the member 51 so as to rotate therewith is a cup-like member 63 which has a flange portion 64 engaging in a recess in the member 51, said member 63 being provided with ears 65 through which the securing members 66 extend, said securing members 66 engaging with suitable openings 10 in the member 51 to secure the members 63 thereto. The member 63 is provided with a projecting hub portion 67 which has an opening 68 therein loosely receiving the polygonal, and preferably square, shaft 69 15 which is secured to the hub by means of a pin 70.

Mounted on the squared shaft 69 so as to be slidable, and non-rotatable, thereon is a collar 71 (Fig. 12) which is provided with 20 the wings or outward projections 72 providing the abrupt shoulders 73 thereon, the opposite sides of the projections 72 being inclined as indicated at 74 to provide cam faces.

25 The member 71 is provided with an outwardly extending hub portion 75 through which the shaft 69 extends, said hub portion being received within a bearing 76 provided in the end of the bracket arm 77 which extends inwardly from the carriage 78. The collar 79 is secured on the hub portion 78 outwardly from the bracket arm 77 to hold the member 71 in assembled relation with the arm 77, the shaft 69 extending 30 through an enlarged opening in the member 77, as will be evident from Fig. 1.

The carriage 78 is adjustably mounted on the transversely extending member 80 of the frame by means of the securing members 81 40 which are screw threadedly engaged with sleeve like members 82 (Fig. 14) having flanges 83 engaging the rear face of the member 80, the heads 84 of the securing members engaging the outer face of the member 78, and washers 85 being provided between said heads and the member 78. Slots 86 are provided in the member 80 receiving the securing members 81 so that when the screw threaded securing members 50 81 are turned outwardly the member 78 can be slid crosswise on the framework on the member 80. As the member 78 is adjusted transversely of the framework, the arm 77 will move therewith and will move lengthwise of the shaft 69 carrying the member 71 and the collar 79, the collar being secured to the hub portion 75 by any suitable means such as the pin 87. The carriage 78 is provided with a substantially semicircular depending portion 88 which is provided with a peripheral flange 89, said flange being thickened at the lower end 90 thereof and being provided with an ear 91 at said lower end thereof that screw threadedly receives 55 the bolt like member 92 upon the unthreaded

portion 93 (Fig. 13) of which is mounted the hub portion 94 of a lever 95, said lever 95 being provided with an adjustable extension 96 held in place by means of the securing members 97, said extension 96 being 70 engaged by the projections 72 on the member 71 to swing said member 95 in a clockwise direction about the pivot 92, as viewed in Fig. 1.

The hub portion 94 is provided with a flattened face 98 from which the lug or finger 99 projects. A bell crank lever 100 is pivotally mounted on the pivot member 101 which is mounted in the depending ear portion 91 of the member 78 and has an arm 102 with which the projection or lug 99 engages. The other arm 103 of the bell crank lever extends upwardly from the pivot 101 and is provided with a reduced end portion 104 with a shoulder 105 adjacent said reduced end portion and with an arcuate cut away portion 106 adjacent the shoulder 105. Secured in fixed position on the arm 103 is an arm 107 which is provided with a curved edge portion 108 and terminates in an upward extension 109. A coil spring 110 extends from the arm 107 to the flange 89, the opposite ends of the spring being hooked in openings in said members 107 and 89 respectively. The tendency, accordingly, is 95 for the bell crank lever to remain in the position shown in Figs. 2 and 7 with the arm 102 in engagement with the projection 99.

The arm 103 is provided with a bore or recess 111 within which the headed member 112 having a head 113 is slidably mounted. The member 112 is further provided with a stem portion 114 (Fig. 7), and a coil spring 115 is mounted between the shoulder formed between the portion 114 and the main body 105 portion of the member 112 and the bottom of the bore 111. The head 113 lies closely adjacent the flat wall portion 116 between the reduced extension 104 and the shoulder 105, and a stop member which may be in the form of a washer 116' is secured to the reduced extension 104 by means of a securing member 117 so as to limit the outward movement of the member 112.

A bearing member 118 having a head 119 and a screw threaded portion 120 engaging with a screw threaded opening in the member 78 is mounted so as to project from the outer face of the member 78. Mounted to rotate on the bearing member 118 is a cutter carrying member 121 from which the knife like cutter member 122 projects, said cutter member having a cutting edge 123 which terminates substantially in a point 124. The cutter member 122 is preferably secured to one face of the member 121, said member 121 being preferably provided with a flange 125 defining a groove 126 and is further provided with a projecting hub portion having the circular portion 127, the polygonal 130

portion 128 and the tubular portion of reduced diameter 129. The polygonal portion 128 is preferably provided with a plurality of elongated flat faces 130, there being eight 5 of such faces shown in the drawings, and with slightly flattened portions 131 alternating with the portions 130. The faces 131, it will be evident, are further from the axis of the member 121 than the faces 10 130.

Mounted on the circular portion 127 of the member 121 is a collar 132 which has the endwise projecting stop lugs 133 and 134 thereon which are received within the groove 15 126. Said collar 132 also has the outwardly projecting stop member 135 thereon which has a substantially radial face 136 providing an abrupt shoulder on one side thereof and which is rounded off as at 137 on the 20 opposite side thereof. When the member 103 is in the position shown in Figs. 2 and 7, the head 113 of the member 112 is engaged by the stop 135, thus holding the member 132 from rotation. The collar 132 25 is further provided with alternating slots 138 and projections 139 forming collectively a slotted flange projecting in the opposite direction from the stop members 133 and 134. The slotted flange portion formed in 30 this manner embraces the polygonal portion 128 of the member 121 and is in turn embraced by the endwise extending annular flange portion 140 on the clutch member 141, said clutch member 141 being provided 35 with a belt groove 142 for receiving a driving belt 143 and is recessed to receive the head 119 of the member 118.

The member 141 is rotated by means of the belt 143 which also passes over the 40 grooved pulley 144 which is slidably mounted on the squared shaft 145. The squared shaft 145 extends through a suitable bearing 146, said bearing 146 being provided on a bracket 147 carried by the depending portion 88 of the member 78, being secured thereto by means of the securing members 148. The member 144 is provided with a sleeve like extension 149 extending through the bearing 146, the bearing 45 being provided with a suitable antifriction lining 150. A collar 151 is pinned to the sleeve like portion 149 to hold the member 144 in position relative to the bearing 146, and a plate 152 is secured to the member 144 by means of the screws or other securing members 153, said plate being provided with a squared opening to receive the shaft 145 whereby the shaft is slidable in 50 the member 144, but will rotate the same.

The bearing bracket 147 is adjustable relative to the member 88 due to the fact that the same is slotted at 154 where the securing members 148 pass therethrough. The shaft 145 also has mounted thereon in fixed 55 position a grooved pulley 155 over which

the belt 156 passes, said belt 156 passing over a suitable driving pulley mounted on the framework of the machine. The pulley 155 is constantly rotated by means of the belt 156 and accordingly the pulley 144 is 70 constantly rotated, rotating the clutch member 141 constantly.

The polygonal portion 128 of the member 121 forms a co-operating clutch member with the clutch member 141, rollers 157 being 75 mounted in the slots 138 in the member 132 and engaging with either the faces 130 or the faces 131 on the member 128. When the rollers 157 are in the position shown in Fig. 7 in engagement with substantially the central portions of the flat faces 130, they are 80 the nearest to the axis of the member 128 and will be out of engagement with the inner face of the flange 140. This is the position of the parts when the stop 135 is in engagement with the head 113. The stop 135 is 85 held in engagement with the head 113 by means of a coil spring 158 mounted in the groove 126 with one end in engagement with the stop pin 159 and the other end thereof 90 in engagement with the stop lug 133. The spring 158 is normally under compression and the stop lug 134 is mounted between the stop member 159 and a stop member 160 which has an outwardly extending stop 95 flange 161. The stop flange 161 engages with the reduced end portion 162 of the stop finger 163 which is mounted upon the pivot member 164 provided on the transversely extending bar 165 extending between the 100 opposite angular flange portions 170 on the member 78. The stop finger 163 is provided with an angular end portion 171 against which the compression spring 172 bears so as to normally hold the member 163 in such 105 a position that the end portion 162 will engage with the stop 161 to prevent clockwise rotation of the member 121 as viewed in Fig. 8. Accordingly, with the spring 158 compressed between the stop 133 and the 110 stop 159, the stop 134 will be in engagement with the stop 160 and the flange 161 on the stop 160 will be in engagement with the end 162 of the stop finger 163, the compression 115 of the spring 158 furthermore holding the stop 135 in engagement with the head 113.

Accordingly, when the member 71 is rotated so that one of the projections 72 thereon engages with the end portion 96 of the lever 95, the downward movement of said end portion will raise the lug 99, rotating the bell crank lever so as to move the head 113 out of engagement with the stop 135, whereupon the spring 158 will act to turn the collar 132 relative to the member 121, moving the rollers 157 from the central portions of the flat faces 130 toward the faces 131, thus carrying said rollers 157 outwardly and into engagement with the flange 130

140. When the rollers 157 engaged with the flange 140 the member 121 is rotated with the member 141, moving the cutter 122 into cutting relation with the squared edge 173 provided on the member 78, thus cutting the strip 25 at this point. However, when the member 51 has made half a turn the stop 53 will engage with the shoulder 55, thus halting the rotation of the squared shaft 69 10 and stopping the member 71 with the member 72 out of engagement with the end 96 of the lever 95. The spring 110 is thus free to restore the bell crank lever 100 to its original position, moving the head 113 of the member 112 into the path of the stop lug 135, thus stopping the member 132 in its rotation when the member 121 has made one complete turn, and with the knife 122 in substantially the position shown in Fig. 2. 15 20 When the lug 135 engages with the head 113 the spring 115 is compressed, absorbing the impact of the parts. However, when the member 132 is halted in its movement, the member 141 continues to rotate, thus causing the rollers 157 to again be carried around to the position shown in Fig. 7, disengaging the member 132 from the member 141, again compressing the spring 158 and thus resetting the clutch for the next actuation thereof. 25 30 This occurs at such a point that the stop finger 163 engages with the stop projection 161 to hold the member 121 from reverse rotation.
- The shaft 52 is preferably an extension of one of the conveyor belt pulley shafts and accordingly the member 71 will rotate in a definite proportion to the rate of travel of the conveyor belts 21 and 22. Accordingly when the member 29 is actuated by one of the articles carried forward by the conveyor, moving the member 37 to such a position as to release the member 51, this will cause the projection 72 on the member 71 to engage with the member 96 at such a time that the strip 25 will be cut by the knife 122, substantially in alignment with the edges of the sheets 23 and 24, the knife 122 rotating rapidly and accordingly cutting substantially instantaneously.
- 50 55 60 65 70 75 80 85 90 95 100 105 110 115 120 125 130
- The plate or bar 165 (Figs. 1, 2 and 3) is preferably provided with a notch 174 to accommodate the fastening member 81 at one end thereof and an opening 175 to accommodate the other fastening member 81 at the other end thereof and is cut away at 176 and 177 to accommodate the moving parts of the device. The depending curved plate-like member 88 is preferably provided with an opening 178 through which an oiled felt covered roller 179 projects so as to engage with the knife 122 to clean any adhesive that may be thereon from the same. The roller 179 is mounted upon a shaft 180 extending through a bearing 181 in the member 88 and held adjustably in position by means of a plate 182 receiving a reduced end portion of the shaft 180, said plate being held in position by means of the fastening member 183. The other end of the shaft 180 is provided with suitable means such as 70 the washer 184 and the cotter pin 185 for holding the rollers in position thereon.
- What we claim and desire to secure by Letters Patent is:—
1. In a machine of the character described, means for conveying articles including a rotatable shaft, a blade, a constantly rotating driving mechanism having friction clutch means for moving the blade including a spring-impelled clutch member for engaging the blade with the driving mechanism, a stop for said member, a stop actuating member, a friction clutch on said conveyor shaft, including an element for tripping said stop actuating member, a latch for said trip element, and means operable by an article being conveyed to trip the latch. 80 85
  2. A machine of the character described including an article conveyor, a carriage adjustable transversely of the conveyor, a blade 90 rotatably mounted in the carriage, a stop for retaining the blade in set position, friction clutch mechanism for rotating and resetting the blade, a spring for moving one clutch member into engagement with the other, a trip for said stop, means for actuating said trip, and a latch for said actuating means operable by an article on the conveyor. 95
  3. In a machine of the character described, a knife, a rotatable member carrying said knife and means for periodically rotating said member to move said knife into cutting position comprising a rotating shaft, a member constantly rotated from said shaft, and means for periodically connecting said members, said last-mentioned means comprising an element having limited movement relative to one of said members and having outwardly movable means engaging the other of said members upon movement relative to 100 said first member. 105 110
  4. In a machine of the character described, a knife, a rotatable member carrying said knife and means for periodically rotating said member to move said knife into cutting position comprising a rotating shaft, a member constantly rotated from said shaft, and means for periodically connecting said members, said last-mentioned means comprising an element having limited movement relative to said knife-carrying member, said knife-carrying member having portions of 115 greater and lesser diameter, and outwardly movable means engaging said element and normally engaging said portions of lesser diameter, but movable outwardly by engagement with said portions of greater diameter to grip said constantly rotating member upon movement of said element relative to 120 said knife-carrying member. 125 130

5. In a machine of the character described, a knife, a rotatable member carrying said knife and means for periodically rotating said member to move said knife into cutting position comprising a rotating shaft, a member constantly rotated from said shaft, and means for periodically connecting said members, said last-mentioned means comprising a collar having limited movement relative to 10 said rotatable member and being provided with openings therein, outwardly movable means in said openings, said rotatable member having portions of greater and lesser diameter embraced by said collar, said outwardly movable means normally engaging said portions of lesser diameter, but being movable outwardly by engagement with said portions of greater diameter to grip said constantly rotating member upon movement 15 of said collar relative to said rotatable member.
6. In a machine of the character described, a knife, a rotatable member carrying said knife and means for periodically rotating 20 said member to move said knife into cutting position comprising a rotating shaft, a member constantly rotated from said shaft, and means for periodically connecting said members, said last-mentioned means comprising 25 a collar having limited movement relative to said rotatable member and being provided with openings therein, rollers mounted in said openings, said rotatable member having portions of greater and lesser diameter embraced by said collar, said rollers mounted 30 normally engaging said portions of lesser diameter, but being movable outwardly by engagement with said portions of greater diameter to grip said constantly rotating member upon movement of said collar relative to 35 said rotatable member.
7. In a machine of the character described, a knife, a rotatable member carrying said knife having a polygonal portion and means 40 for periodically rotating said member to move said knife into cutting position comprising a rotating shaft, a member having an endwise projecting annular flange thereon constantly rotated from said shaft and 45 means for periodically connecting said members comprising a collar embracing the polygonal portion of said rotatable member and rotatable in said annular flange, said collar having openings therein, and rollers 50 mounted in said openings and engaging the polygonal portion of said rotatable member, said rollers being normally out of engagement with said annular flange but being movable into engagement therewith upon 55 relative movement of said collar and said rotatable member.
8. In a machine of the character described, a rotatable member, a knife mounted thereon and means for periodically rotating said 60 member to move said knife into cutting position comprising a clutch member, resilient means interposed between said rotatable member and said clutch member, a stop engageable by said clutch member, said resilient means being compressed when said clutch member is engaging said stop, a co-operating clutch member, means for rotating said co-operating clutch member, and means actuated by said resilient means to engage said clutch members when said stop is moved out of engagement with said first clutch member.
9. In a machine of the character described, a rotatable member, a knife mounted thereon and means for periodically rotating said member to move said knife into cutting position comprising a clutch member, resilient means interposed between said rotatable member and said clutch member, a stop engageable by said clutch member, said resilient means being compressed when said clutch member is engaging said stop, means for holding said rotatable member against reverse rotation when said clutch member is engaging said stop, a co-operating clutch member, means for rotating said co-operating clutch member, and means actuated by said resilient means to engage said clutch members when said stop is moved out of engagement with said first clutch member.
10. In a machine of the character described, a rotatable member, a knife mounted thereon and means for periodically rotating said member to move said knife into cutting position comprising a clutch member, resilient means interposed between said rotatable member and said clutch member, a stop engageable by said clutch member, said resilient means being compressed when said clutch member is engaging said stop, a co-operating clutch member, means for rotating said co-operating clutch member, and means actuated by said resilient means to engage said clutch members when said stop is moved out of engagement with said first clutch member, said first clutch member and said rotatable member having engaging means to positively drive said rotatable member when said stop is disengaged therefrom.
11. In a machine of the character described, a rotatable member, a knife mounted thereon and means for periodically rotating said member to move said knife into cutting position, comprising a clutch member, resilient means interposed between said rotatable member and said clutch member, a stop engageable by said clutch member, said resilient means being compressed when said clutch member is engaging said stop, a co-operating clutch member, means for rotating said co-operating clutch member, means actuated by said resilient means to engage said clutch members when said stop is moved out of engagement with said first clutch member, and stop releasing means actuated by the articles to be acted on by said knife.

12. In a machine of the character described, means for conveying articles in a predetermined path, cutting mechanism adapted to operate on said articles, and means for actuating said cutting means comprising a member engaged by said articles as the same are moved along by said conveying means, a rotatable member, releasable means normally holding said rotatable member against movement and movable out of holding position when said first member is engaged by one of said articles to permit said rotatable member to move through a predetermined arc, a clutch mechanism for driving said cutting mechanism and a stop for holding said clutch mechanism in inoperative position, said stop being moved out of holding position upon movement of said rotatable member through said arc.
13. In a machine of the character described, a framework, a conveyor extending longitudinally of said framework, cutting mechanism mounted on a carriage adjustable transversely of said framework, clutch mechanism on said carriage for periodically operating said cutting mechanism, means on said carriage for holding said clutch mechanism in disengagement and means for releasing said holding means, comprising a member on said framework engaged by articles on said conveyor at a predetermined point in their movement and means for actuating said releasing means actuated by said member, said last-mentioned means comprising elements mounted on said framework and elements adjustable with said carriage.
14. In a machine of the character described, a framework, a conveyor extending longitudinally of said framework, cutting mechanism mounted on a carriage adjustable transversely of said framework, clutch mechanism on said carriage for periodically operating said cutting mechanism, means on said carriage for holding said clutch mechanism in disengagement and means for releasing said holding means, comprising a member on said framework engaged by articles on said conveyor at a predetermined
- 5 point in their movement and means for actuating said releasing means actuated by said member, said last-mentioned means comprising elements mounted on said framework and elements adjustable with said carriage and embodying a sliding connection.
15. In a machine of the character described, a framework, a conveyor extending longitudinally of said framework, cutting mechanism mounted on a carriage adjustable transversely of said framework, clutch mechanism on said carriage for periodically operating said cutting mechanism, means on said carriage for holding said clutch mechanism in disengagement and means for releasing said holding means, comprising a member on said framework engaged by articles on said conveyor at a predetermined point in their movement and means for actuating said releasing means actuated by said member, said last-mentioned means comprising elements mounted on said framework and elements adjustable with said carriage and comprising an axially slid able, rotatable member.
16. In a machine of the character described, a framework, a conveyor extending longitudinally of said framework, cutting mechanism mounted on a carriage adjustable transversely of said framework, clutch mechanism on said carriage for periodically operating said cutting mechanism, means on said carriage for holding said clutch mechanism in disengagement and means for releasing said holding means, comprising a member on said framework engaged by articles on said conveyor at a predetermined point in their movement and means for actuating said releasing means actuated by said member, said last-mentioned means comprising elements mounted on said framework and elements adjustable with said carriage and comprising an axially slid able, rotatable member, rotatable through a predetermined arc to trip said releasing means.

In testimony whereof we affix our signatures.

EDWARD M. BRACKETT.
